UNITED STATES PATENT OFFICE.

FRANK J. LEARMAN, OF BUFFALO, NEW YORK, ASSIGNOR TO BUFFALO SPECIALTY COMPANY, OF BUFFALO, NEW YORK, A CORPORATION OF NEW YORK.

POLISHING MOP.

Application filed May 8, 1920. Serial No. 379,853.

To all whom it may concern:

Be it known that I, FRANK J. LEARMAN, a citizen of the United States, residing at Buffalo, in the county of Erie and State 5 of New York, have invented certain new and useful Improvements in Polishing Mops, of which the following is a specification.

My invention relates to improvements in 10 polishing mops, and has particular reference to the handle and the manner of fastening the same to a mop head.

The primary object of my invention is to provide a simple and inexpensive polishing 15 mop having new and improved means for securing the mop head to the handle so that the handle may be easily adjusted upon the mop while manipulating the mop and so that the handle may be retained in 20 any adjusted position.

A further object of my invention is to provide means for fastening a handle to a mop head or other article of utility in which the usual socket to receive the handle 25 is dispensed with, said means retaining all the advantages of a handle inserted into a socket and adding thereto advantages not possessed by such a handle.

A still further object is the production 30 of a neat appearing connection between the handle and a mop head or other article of utility and which has few parts and is easily adjusted.

With these and other objects in view, the 35 invention consists in the novel features of construction, and in the arrangement and combination of parts to be hereinafter described and more particularly pointed out in the subjoined claims.

40 In the drawings:-

Fig. 1 is a perspective view of a mop showing the upper portion of the handle broken away, the usual swab or mopping element being omitted.

45 Fig. 2 is a side elevation of the same.

Fig. 3 is an enlarged transverse section taken on line 3—3, Fig. 2.

Fig. 4 is an enlarged transverse section taken on line 4—4, Fig. 2.

50 Fig. 5 is a longitudinal section through the lower end of the handle showing the manner of clamping the transverse pivot portion of a mop head therein.

Fig. 6 is a detached perspective view of

the upper clamping member of the handle. 55

Fig. 7 is a detached perspective view of the lower clamping member of the handle.

Fig. 8 is a perspective view of a modified form of my invention, showing a portion of the lower end of the handle, and the 60 clamping means whereby the pivot portion of the mop head is clamped in said handle.

Fig. 9 is a section taken on line 9—9, Fig. 10.

Fig. 10 is a transverse section taken on 65 line 10—10, Fig. 9.

Fig. 11 is a side elevation of a still further modified form of my invention.

Fig. 12 is a longitudinal section taken on 70 line 12—12, Fig. 11.

Fig. 13 is a longitudinal section taken on line 13—13, Fig. 12.

Fig. 14 is an enlarged transverse section taken on line 14—14, Fig. 13.

The reference numeral 1 designates a 75 mop head, 2 a handle and 3 the clamping means considered as a whole whereby the mop head may be clamped within the handle.

The mop head shown is adapted for use 80 in connection with a polishing swab or mopping element (not shown) and is formed of wire bent into any desired outline and having a transverse pivot portion 4. The type of mop head shown is adapted 85 to have a polishing swab slipped thereon, the swab being of any desired construction and being commonly known in the art to which this invention relates.

The handle 2 is provided with a longitudinal slot 5 extending from its lower or inner end upwardly or outwardly, opposite faces of the slot being provided with transversely-disposed curved notches or depressions 6, the opposite notches or depressions forming a substantially transverse circular opening through the handle which the slot 5 intersects. The pivot portion 4 of the 90

mop head or other article of utility is passed through the circular opening formed by the notches 6 and is preferably grooved or otherwise roughened so that the parts of the handle on opposite sides of the slot will 95

firmly engage said pivot portion. I preferably provide that part of the pivot portion lying within the handle with V-shaped peripheral grooves forming a series of sharpened ridges 7 adapted to bite into the fibers 100 105

of the wooden handle when the mop head is tightened therein, as will be presently explained, but it is to be understood that for certain purposes, the pivot portion may be 5 left perfectly smooth so that it has a smooth unbroken surface from end to end.

The clamping means 3 is preferably in the form of two crescent-shaped members 8, 9 embracing, respectively, the upper and lower 10 portions of the handle separated by the slot 5, the member 9 having centrally between its ends an upstanding threaded stem 10 which is passed through aligned openings 11 in the upper and lower portions of the handle and 15 also through an opening 12 formed in the upper clamping member 8. This stem is of sufficient length to extend upwardly above the outer surface of the clamping member 8 for the purpose of applying a clamping or 20 thumb nut 13 thereon between which and said clamping member 8 a washer 14 is applied. Said washer is preferably formed of fiber so as to provide the necessary friction to guard against accidental unthreading of 25 the clamping or thumb nut 13.

With the pivot portion 4 of the handle passed through the transverse opening formed by the concaved notches 6 and the two clamping members applied to the separated 30 parts of the handle, these separated parts will be forced together upon tightening the nut 13 so that the sharpened ridges 7 on said pivot portion will bite into the fibers of the wooden handle and thus prevent 35 displacement of the handle laterally, at the same time increasing the friction between the pivot portion and the handle so that the handle will not swing on the pivot portion of the mop head, except when considerable 40 force is applied, either downwardly or upwardly on the handle to cause a change in the angular position of the latter.

In the modification shown in Figs. 8 to 45 10 inclusive, that part of the pivot portion passing through the transverse opening intersected by the slot 5 is perfectly smooth, and at opposite sides of the handle this pivot portion is provided with annular grooves 15 50 into which opposite end portions of the upper clamping member 8^a is adapted to be entered. This upper clamping member 8^a differs from the clamping member 8 in that it has its extremities at opposite sides of the 55 handle continued to a point beyond the slot 5 so that it will enter the annular grooves 15 at the front of the pivot portion. In other respects the clamping means is exactly as shown in and described with reference to 60 the preceding figures except that the lower clamping member 9^a is made somewhat shorter than the clamping member 9.

By entering the opposite ends of the upper clamping member 8^a into the circumferential 65 grooves 15 of the pivot portion 4, lat-

eral displacement of the handle from the mop head is prevented, and this pivot portion is clamped between the separated parts of the handle by tightening the thumb nut 13 in the same manner as the pivot portion 70 in the preferred construction is clamped when tightening the clamping or thumb nut thereof.

In the modification shown in Figs. 11 to 14 inclusive, 2^b designates the handle which is provided at its inner or lower end with a transverse slot 16 extending inwardly from its extremity and terminating at its inner end in a circular transverse opening 17 in which the pivot portion 4 of the mop head is adapted to be inserted. The clamping means employed in this case comprises an upper crescent-shaped clamping member 8^b having a threaded stem 18 extending from its inner face, and this threaded stem is adapted to pass through an opening 19 in the handle 2^b and project through the handle at the bottom thereof. A second crescent-shaped clamping member 9^b is provided with an opening 20 through which said stem projects, said clamping member 9^b bearing against the handle, as best shown in Fig. 14. A nut 13 is applied to the threaded portion of this stem, and between this nut and the clamping member 9^b a washer 14 is interposed.

The pivot portion 4 of the mop head is provided with an annular groove 21 and the threaded stem of the clamping member 8^b is fitted in said groove, as best shown in Fig. 12, thus preventing lateral movement of the handle on said pivot portion while allowing the handle to be swung to any desired angle.

As in the previous constructions, the degree of friction applied to the pivot portion is regulated by the thumb nut 13, and upon tightening this nut the spaced parts at opposite sides of the slot 16 in the handle are drawn together and create the necessary friction against said pivot portion.

Having thus described my invention, what I claim is:

1. The combination of a handle having a longitudinal slot therein, a mop head 115 having a transverse pivot-portion extending through the slot of said handle, and clamping means on said handle between the end thereof and said pivot portion whereby said pivot-portion is clamped within said handle 120 yet permitted to rotate therein.

2. The combination of a handle provided with a longitudinal slot at one end and having opposite walls of said slot provided with transverse depressions, a mop head having 125 a transverse pivot-portion arranged in said depressions, and means between said pivot portion and the end of said handle for clamping the parts of the handle at opposite sides of said slot together to friction- 130

ally bind said pivot-portion within said depression yet permit said pivot-portion to rotate within said depression.

3. In a device of the kind described, the combination of a handle having a longitudinal slot at one end thereof, means to force the separated parts of said handle at opposite sides of said slot together, and a mop head having a transverse pivot-portion extending through the slot of said handle, said pivot-portion having means co-acting with another part of said device to prevent lateral movement of said handle with respect to said mop head.

15 4. In a device of the kind described, the combination of a handle having a longitudinal slot at one end thereof, clamping means for drawing the separated parts at opposite sides of said slot together, and a 20 mop head having a transverse pivot-portion passed through said slot and provided with circumferential grooves adapted to receive other parts of the device therein to prevent lateral movement of said handle with respect to said mop head.

25 5. In a device of the kind described, the combination of a handle having a longitudinal slot at one end thereof, a mop head having a transverse pivot-portion passed 30 through said slot, and a clamping means between said pivot-portion and the end of said handle for clamping the separated parts of said handle firmly against said pivot-portion, the part of said transverse 35 pivot-portion within said slot being roughened to prevent relative movement laterally of said handle and mop head.

6. In a device of the kind described, the combination of a handle having a narrow 40 longitudinal slot extending transversely therethrough and being provided with con-

caved depressions in opposite walls of said slot to form a transverse substantially-circular opening through said handle intersected by said slot, a mop head having a 45 transverse pivot-portion fitting into said transverse opening, and clamping means to cause the separated parts of said handle at opposite sides of said slot to frictionally bind against said pivot-portion, said pivot-portion having means co-operating with another part of the device to prevent lateral movement of said handle on said mop head.

7. The combination of a handle having a longitudinal slot at one end thereof, a mop 55 head having a pivot portion extending through said slot, a crescent-shaped clamping member embracing that portion of the handle below said slot between said pivot portion and the end of said handle and having an upstanding stem between its ends threaded at its outer end and passed through the separated parts of said handle, a crescent-shaped clamping member embracing the part of said handle above said slot and having an opening therein through which the stem of said first-mentioned clamping member passes, and a clamping nut threaded onto the projecting threaded end of said stem and adapted to force the separated 60 parts of said handle together to clamp said pivot-portion therebetween.

8. In a device of the kind described, a handle having a longitudinal slot at one end thereof, an article of utility having a 75 pivot portion extending through said slot, and co-acting means on said pivot portion and other parts of the device to retain said pivot portion against movement lengthwise therein.

In testimony whereof I affix my signature.
FRANK J. LEARMAN.
